ILLUMINATING SYSTEM

Aart de Bruin, Eindhoven, Netherlands, assignor
to General Electric Company, a corporation of
New York

Application July 30, 1935, Serial No. 33,904
In Germany July 30, 1934

1 Claim. (Cl. 176—124)

The present invention relates to illuminating systems comprising a plurality of gaseous electric discharge devices, each of which has an electrode which is electron emitting when heated.

5 Each lamp in such a system is usually provided with a transformer to supply the heating current for the electron emitting electrode and has a choke coil connected in series therewith to regulate the discharge current. Both the 10 lamp and the transformer are connected to the same current source, preferably a 220 volt alternating current source. Frequently, however, the available current source in the locality in which the system is to be installed is not a 220 15 volt source and, in fact, the voltage of the available current source may be anywhere within a range of 200 to 260 volts. In order to meet this situation both the choke-coil and the transformer can be provided with taps whereby the 20 current flow through the lamp and the heating current for the electron emitting electrode can be adjusted to the desired magnitude. In certain types of systems in which the transformer and the choke coil are located in separated positions the adjustment of the taps on the choke coil and 25 on the transformer is complicated. In highway illuminating systems, for example, the choke coil is mounted on the lower part of the supporting pole for the lamp and the transformer is mounted in the lamp fixture at the top of the 30 pole.

The object of the present invention is to provide an illuminating system of the above type which is easily adapted to operate on voltages 35 within a comparatively large range. Still further objects and advantages attaching to the device and to its use and operation will be apparent to those skilled in the art from the following particular description.

40 The invention attains its object by providing the choke coil with taps and by connecting the primary of the transformer to the choke coil in such manner that a part of the choke coil can be connected into the circuit of the transformer primary and the current source. The 45 choke coil can thus also operate as an auto-transformer. The voltage impressed on the transformer primary equals the voltage of the current source plus the voltage of that part of the choke coil connected into the circuit of said 50 transformer primary. It is thus a simple matter to arrange the taps on the choke coil in such manner that substantially the same voltage is impressed on the transformer primary and substantially the same current flows through the 55

lamp whether the voltage of the current source is 200 volts, 260 volts or any voltage within this range. When the voltage of the current source corresponds exactly to the voltage for which the transformer is designed the taps on the choke 5 coil are arranged in such manner that no part of the choke coil is connected in the circuit of the transformer primary. The above described circuit can thus be adjusted to operate on current sources having a voltage within the range 10 of 200 to 260 volts by a simple arrangement of the taps on the choke coil.

In the drawing accompanying and forming part of this specification two embodiments of the invention are shown, in which 15

Fig. 1 is a schematic view of one embodiment of the invention, and

Fig. 2 is a similar view of another embodiment of the invention.

Referring to Fig. 1 of the drawing the new 20 and novel illuminating system comprises a gaseous electric discharge lamp of the positive column type having a U-shaped tubular container 1. Said container 1 has a gaseous atmosphere 25 therein comprising a rare gas, such as neon, a metal vapor, such as mercury or sodium vapor, or a mixture of a starting gas, such as neon, argon, krypton, or mixtures thereof, and a vaporizable material, such as sodium, the vapor of which is light emitting during the operation of 30 the device. Said container 1 has electrodes 2 and 3 sealed therein at the ends thereof. Said electrodes 2 and 3 consist of a coiled filament, such as a tungsten filament, having a coating 35 of electron emitting material, such as barium oxide, thereon. Each of said electrodes 2 and 3 is connected to the secondary coils 4 and 5, respectively, of the heating-current transformer 6. The primary 7 of said transformer 6 is connected directly to the electrode 3 and to the terminal 8 of an alternating current source 9. Said electrode 2 is connected to the end 14 of the choke-coil 10 which is connected in series with the gaseous electric discharge lamp. Said choke-coil 10 has a plurality of taps a, b, c, d, e, f and 45 g thereon. One of said taps is connected by lead 11 to the terminal 12 of said current source 9. The transformer primary 7 is connected by lead 13 to one of the taps on said choke coil 10.

Assuming that the above described circuit is 50 to be connected to an alternating current source 9 the voltage of which may be anywhere within a range of 200 to 260 volts the taps are located in such manner on the choke coil 10 that the current flow through the lamp and the voltage ap- 55

plied across the terminals of the transformer primary 7 can be adjusted to that value for which the lamp and the transformer are designed whether the voltage of the current source 9 be 5 200 volts, 260 volts or anywhere within these limits. For example, when the voltage of the current source 9 is 260 volts and the transformer 6 is designed to furnish the desired heating current for the electrodes 2 and 3 when this voltage 10 is impressed on the primary 7 thereof the connections of the leads 11 and 13 to the taps on the choke coil are arranged as follows. First the lead 11 is connected to that tap on the choke coil 10, tap *d* for example, which connects a sufficient 15 part of the choke coil 10 in series with the lamp to regulate the flow of current through the lamp to that value at which said lamp is designed to operate at maximum efficiency, hereinafter termed the normal value. Then the lead 13 is 20 connected to the same tap *d* on said choke coil 10 so that no part of the choke coil 10 is connected in series with the transformer primary 7.

When the voltage of the current source 9 is 230 volts a smaller part of the choke coil 10 is 25 connected in series with the lamp and a sufficient part of said choke coil 10 is connected in series with the transformer primary 7 to regulate the current flow through the lamp to the normal value thereof and apply a voltage of 260 volts 30 across the transformer primary 7. For example, the lead 11 is connected to the tap *c* and the lead 13 to tap *e* on said choke coil 10.

When desired the transformer 6 is designed to supply a heating current of the desired magnitude 35 on a voltage in the middle of the voltage range within which the system is designed to operate. For example, when the voltage of current source 9 is within the range of 200 to 260 volts the transformer 6 is designed to supply a heating current of the desired magnitude when 40 230 volts is applied across the primary 7 thereof. When current source 9 has a voltage of 230 volts the leads 11 and 13 are connected to the same tap on said choke coil 10. When the voltage of the 45 current source is other than 230 volts but is within the range of 200 to 260 volts the leads 11 and 13 are connected to different taps on the choke coil 10 to connect a larger or smaller part of the choke coil 10 in series with the lamp and the 50 transformer primary 7.

The embodiment of the invention illustrated in Fig. 2 of the drawing is similar in all respects to the embodiment illustrated in Fig. 1 except that in this embodiment the lead 13 is permanently 55 connected to the end 15 of the choke coil 10 and an auxiliary electrode 17 is mounted on the bend on the lamp container 1 which electrode 17 is connected to a special coil 18 on the transformer primary 7. Said auxiliary electrode 17 facilitates 60 the starting of the gaseous electric discharge between the electrodes 2 and 3 of the lamp. When the voltage of the current source 9 is 260 volts and the transformer 6 is designed for a voltage of 260 volts impressed on the primary 7 the lead

11 is connected to the end 15 of said choke coil 10. Said choke-coil 10 is, of course, designed to regulate the discharge current in the lamp to the normal value thereof at the voltage of the current source 9, 260 volts. When the voltage of the 5 current source 9 is 200 volts the lead 11 is connected to the tap *a* on said choke coil 9 which cuts out of the lamp circuit a part of the choke coil 9 and connects said choke-coil part in series with the transformer primary 7. The tap *a* on the choke coil 10 is at a part thereof whereby the discharge current in the lamp is regulated to the normal value thereof when the voltage of the current source 9 is 200 volts.

It is apparent that in the embodiment of the 15 invention illustrated in Fig. 2 the voltage across the transformer primary is different with different current source voltages. When the voltage of the current source 9 is 260 volts the voltage impressed on the transformer primary 7 is 260 20 volts. When the current source 9 has a voltage of 200 volts the voltage impressed on the transformer primary 7 is 227 volts. When the system is designed to operate on current sources of 200 to 260 volts and the transformer is designed for 25 260 volts the voltage impressed on the transformer primary is anywhere from 227 to 260 volts. When the transformer is designed for 230 volts the voltage impressed on the primary thereof is 30 anywhere from 214 to 244 volts. The only disadvantage of this variation of voltage impressed on the primary 7 with current sources of different voltage is that the electrodes 2 and 3 take a longer time to attain the operating temperature thereof on a current source voltage of 200 volts than on 35 a current source voltage of 260 volts. This is counterbalanced however by the advantage of having but one lead 11 on the choke coil 10 which is adjusted to adapt the system to different current supply voltages.

While I have shown and described and have pointed out in the annexed claim certain novel features of the invention, it will be understood that various omissions, substitutions and changes in the forms and details of the device illustrated 45 and in its use and operation may be made by those skilled in the art without departing from the broad spirit and scope of the invention.

What I claim as new and desire to secure by Letters Patent of the United States, is:—

An illuminating system comprising in combination, an alternating current source, a gaseous electric discharge device comprising an electrode which is electron emitting when heated, a choke coil connected in series with said lamp and a 55 transformer connected in parallel with said lamp across the terminals of said current source, said choke coil having a plurality of taps along the length thereof, one of the current leads for said transformer being connected to one of said taps, the current lead connecting said choke coil to a terminal of said current source being connected to a tap on said choke coil.

AART DE BRUIN.
